CYLINDER LOCK ASSEMBLY TOOL

Harry Selditch, Philadelphia, Pa.

Application November 10, 1953, Serial No. 391,196

2 Claims. (Cl. 81—5.1)

This invention relates generally to means for inserting pins into bodies provided with pin receiving openings and more particularly is concerned with an improved tool for handling during assembly the pins of a cylinder lock.

A principal object of the present invention is to incorporate in a tool for inserting the pins into the pin receiving bores in the cylinder of a cylinder lock, means for urging a pin into its pin receiving bore simultaneously as the hold of the tool on the pin is relaxed.

Another object of the present invention is to provide such a tool with means for supporting and guiding a pin after the hold of the tool on the pin is relaxed.

Other objects and advantages of the present invention will appear more fully hereinafter, it being understood that the present invention consists substantially in the combination, construction, location and general arrangement of parts, all as described in detail in the following specification, as shown in the accompanying drawing and as fully pointed out in the appended claims.

In the accompanying drawings:

Figure 1 is a perspective view showing in use a tool embodying the present invention;

Figure 2 is a plan view of the tool shown in Figure 1;

Figure 3 is a side view of the tool holding a pin;

Figure 4 is an enlarged vertical section taken on line 4—4 of Figure 2;

Figure 5 is the same as Figure 4 but shows the tool about to be withdrawn after its hold on the pin has been relaxed;

Figure 6 is an enlarged bottom view taken on the line 6—6 of Figure 2; and

Figure 7 is the same as Figure 6 but omits the jaws of the tool opened.

Referring to the drawings, a tool embodying the present invention may comprise essentially a pair of pliers including sections pivotally secured together as at 10 and having respectively handle parts 11 and 12 and respectively jaw parts 13 and 14. The jaws 13 and 14 are flat elongated parts disposed in coplanar relation, and the corresponding terminal portions thereof are provided respectively with a pair of grooves 15—15 which when the jaw parts 13 and 14 are closed conjointly form a vertically extending aperture adapted to receive a pin.

A leaf spring 16 is disposed in close overlying relation to the jaw parts 13 and 14, one end portion of the leaf spring 16 being suitably anchored to the jaw part 13 as by welding at 17, and the opposite end portion thereof being freely disposed over the terminal portions of the jaws 13 and 14. The latter end portion of the leaf spring 16 fixedly mounts an elongated depending element 18 which projects freely into the aperture formed by the grooves 15—15.

In the assembly of a cylinder lock, using the tool of the present invention, the pins are inserted in the pin receiving bores in the cylinder by the following procedure. Referring particularly to Figure 1, the cylinder 19 is held so that its axially extending plug opening 20 is positioned horizontally and the communicating laterally extending pin receiving bores 21 are positioned vertically, extending downwardly from the plug opening 20. Now referring particularly to Figures 4 and 6, a pin 22 is placed between the terminal portions of the jaw parts 13 and 14 of the tool of the present invention, the opposite sides of the pin 22 being seated respectively in the grooves 15—15. The pin 22 is additionally positioned so that its upper end abuts the lower end

2

of the element 18 and so that the leaf spring 16 is flexed, the lower terminal portion of the pin 22 being disposed below the undersurface of the jaws 13 and 14. Referring particularly to Figure 1, with the pin 22 firmly held as described, the jaw parts 13 and 14 are projected as shown into the plug opening 20, and the pin 22 is held over its pin receiving bore 21, the latter already having been fitted with a coil spring 23. The pin 22 is now moved about until the lower terminal portion thereof is in registry with the pin receiving bore 21 whereupon the pin 22 is released by the operator merely relaxing his grip on the handle parts 11 and 21. The energy previously stored in the leaf spring 16 being released, the leaf spring 16 returns to its normal unflexed position closely overlying the jaws 13 and 14, as a consequence of which the leaf spring 16 through the medium of the element 18 exerts a downward force upon the pin 22, whereupon the latter moves downwardly into its pin receiving bore 21.

It will be noted that the downward force aforementioned is exerted upon the pin 22 simultaneously as the operator's grip on the handles 11 and 12 is relaxed, without any other movement of the tool, and additionally that the aperture formed by the grooves 15—15 affords a way for supporting and guiding the pin 22 in its axial movement downwardly into its pin receiving bore 21. Subsequently, the tool may be applied to the top of the pin 22 and the latter pushed downwardly against the force of the coil spring 23 a distance sufficient to permit insertion of a dowel or similar device 24 into the plug opening 20 to a position over the pin 22 for maintaining the same fully projected into its pin receiving bore 21 while the remaining pins are handled successively in a similar manner.

As the several pins 22 are successively fitted into their respective bores 21, the dowel 24 is advanced axially into the plug opening 20 until all of the seated pins are covered by the dowel, following which the dowel is replaced by the rotatable plug (not shown) of the lock assembly, which plug is conventionally fitted with spring-pressed pins and is longitudinally slotted to receive the plug-actuating key.

In the assembly of a cylinder lock without the tool of the present invention, the pins are inserted in the pin receiving bores in the cylinder in accordance with the following more or less conventional procedure. The cylinder, free of its rotatable plug, is held as described hereinabove. The pin to be inserted is then picked up with tweezers and inserted into the plug opening, being held over the pin receiving bore in a vertical position with the lower end portion of the pin projecting below the tweezers. While thus held, the pin is moved about until the lower end portion thereof is in registry with the pin receiving bore, whereupon the pin is released and then pushed into the pin receiving bore by suitably applying the tweezers to the top of the pin. From the movement when the hold of the tweezers on the sides of the pin is relaxed until the tweezers are applied to the top of the pin as aforementioned, the pin is unsupported and unguided, as a consequence of which it often happens that a pin moves out of registry with its pin receiving bore before it can be pushed into the same, making it necessary to start all over again. For this reason, the use of tweezers or other ordinary tools has not proved to be entirely satisfactory.

It will be understood, of course, that the tool as hereinabove shown and described is susceptible of various changes and modifications which may be made from time to time without any departure from the general principles or real spirit of the present invention. The jaw parts described hereinabove might be, for example, the legs of the generally U-shaped resilient member.

Furthermore, the leaf spring might be replaced by a suitably arranged coil spring. Accordingly, it is intended to claim the present invention broadly, as well as specifically, as indicated in the appended claims.

What is claimed as new and useful is:

1. A tool comprising a pair of flat elongated jaw parts secured together for coplanar pivotal movement and having corresponding end portions provided respectively with a pair of grooves which conjointly form an aperture

adapted to receive a pin, said jaws being thus adapted for releasably holding the latter with its longitudinal axis extending laterally of the jaws, and yieldable means including a leaf spring overlying said jaws and anchored to one of the latter, the free end portion of said leaf spring being adapted for engagement with one end portion of the pin, and said leaf spring being adapted for storing energy when the pin is held as aforesaid and releasing the energy simultaneously as the hold of said jaws on the pin is relaxed, said leaf spring being operative upon release of the stored energy to move the pin axially, and said grooved corresponding end portions of the jaws being adapted to support and guide the pin during its axial movement.

2. A tool comprising a pair of flat elongated jaw parts 15 secured together for coplanar pivotal movement and having corresponding end portions provided respectively with a pair of grooves which conjointly form an aperture adapted to receive a pin, said jaws being thus adapted for releasably holding the latter with its longitudinal 20 axis extending laterally of the jaws, and yieldable means

including a leaf spring overlying said jaws and anchored to one of the latter, and an elongated element extending laterally from the free end portion of said leaf spring and freely into said aperture, said element being adapted for engagement with one end portion of the pin, and said leaf spring being adapted for storing energy when the pin is held as aforesaid and releasing the energy simultaneously as the hold of said jaws on the pin is relaxed, said leaf spring being operative upon release of the stored energy to move the pin axially, and said grooved corresponding end portions of the jaws being adapted to support and guide the pin during its axial movement.
